BUILDING HOUSES OF ARTIFICIAL STONE

Axel Fritiof Bomgren, Storangen, Sweden

Application August 31, 1937, Serial No. 161,862
In Sweden June 15, 1935

3 Claims. (Cl. 72—16)

The present invention relates to a method of erecting buildings of artificial stone and binding such stones.

In the building art attempts have been made for years to apply to the greatest extent possible industrial methods in the production of buildings in order thereby to reduce the cost of construction, particularly as regards smaller dwelling houses. As a step in said endeavours various systems have been worked out for building houses of parts industrially made ready for erecting. It has been possible to build only wooden houses economically in this manner. The property of wood of taking up water during moist weather at the same time changing its shape in an often very irregular manner involves certain inconveniences, since the individual parts must meet exceedingly strict requirements with regard to dimensions and permanency of shape.

Such inconveniences are avoided according to the present invention which relates to a method of producing houses from ready made parts consisting of a material having a greater permanency of shape than wood, namely a stone-like material. The present invention has for its primary object to utilize porous concrete for producing houses from parts industrially made ready for erection, although other castable stone-like materials having similar properties can be utilized. In accordance with the invention wall blocks are made industrially from porous concrete, the individual wall blocks being made of a height equal to that of a full story.

Ready made building parts consisting of porous concrete cannot be joined together in the same manner as parts of wood. The most simple method would seem to be to set the parts in mortar as they are placed in position. It is, however, only with difficulty that parts of the size in question—the individual parts often having a weight of some 400 kilograms—can be placed correctly in position in this manner. According to a preferred embodiment of the invention the wall blocks are initially erected on the foundation wall or on each other respectively without joining the blocks together while inserting spacers between the blocks so that open joints of the desired thickness are formed between the blocks. Thus erection is facilitated, and it becomes possible to adjust the blocks with respect to each other after all blocks belonging to the same story have been erected. After the blocks have been adjusted they are rigidly secured in the adjusted positions to prevent displacements and are thereafter rigidly united with the foundation and with

each other respectively by grouting the joints with a binding composition, for instance cement mortar. The grouting of the joints can be carried out by first closing the openings both of the horizontal and of the vertical joints flush with the surfaces of the walls so that a system of mutually communicating vertical and horizontal closed channels are formed, whereupon cement mortar or other liquid joint filling material is poured into the joints so that the joints are completely filled with the joint composition which after solidification securely holds the different wall blocks together.

It has been found possible to obtain according to the present invention perfectly plane blocks which can be adjusted so accurately with respect to each other that interior and exterior plastering can be dispensed with. On the inside the wall can be directly papered or painted, and on the outside it can be coated or sprayed with a paint capable of repelling water.

By industrially producing the wall blocks of porous concrete the joint surfaces of the blocks can be made so smooth and plane as to render possible a considerable reduction of the thickness of the joints, this being of considerable importance in view of the fact that cement binding composition, has a very much higher heat conductivity than the porous concrete. Even when the wall blocks have a small thickness the heat transmitting capacity of the joints can therefore be made sufficiently low by correspondingly reducing the thickness of the joints. As a result of the thin joints the amount of moisture introduced into the building through the joint mortar is also reduced to a minimum, so that the building can be used immediately after completion without having to be first subjected to a time-wasting drying-out operation.

The floors can also be made from industrially cast floor slabs consisting of porous concrete or other artificial stone. Said floor construction involves the advantage that the stone floor can be immediately used without having to be subjected to a previous time-wasting drying-out operation.

In order that the invention may be clearly understood and readily carried out the same will now be described more fully with reference to the accompanying drawings, in which:

Figure 1 is a front view of the lower corner portion of a house built according to the invention, the house being shown with open joints to show the spacers more clearly.

Figure 2 is a plan view on the line 2—2 in Figure 1;

Figures 3 to 5 show on a larger scale and in front view, side view and plan view respectively a portion of an outer wall provided with a door opening;

5 Figure 6 is a part section illustrating the manner of erecting the floor beams;

Figure 7 is a section through the flooring;

Figure 8 is a plan view of a corner formed of two outer walls;

10 Figure 9 is a plan view of the meeting point between an outer wall and an inner wall;

Figure 10 shows a method of closing the joint openings before pouring the cement mortar into the joints;

15 Figure 11 is a plan view of one corner of a building under erection having the wall blocks of the first story in position and the joint openings sealed by means of a sealing composition before pouring the binding mass into the joints;

20 Figure 12 is a vertical section on the line 12—12 in Figure 11.

Referring to the drawings, 9 designates the foundation wall on which a number of wall blocks 10 and 15 having the height of a full story are erected, spacers 12 being inserted between the foundation wall and the wall blocks standing thereupon and between the wall blocks mutually so that open throughgoing joints having a small

30 thickness, preferably amounting to 5 to 8 millimeters or less, are formed. The wall blocks 10 and 15 are cast in a factory from porous concrete or other mouldable stone-like material with similar low specific weight and good heat insulating capacity and are transported in ready condition to the place of erection, the blocks being slightly reinforced, if necessary, to permit of handling during transport. The spacers 12

35 are preferably made from fiber or similar material and can be secured to the respective wall blocks in connection with the casting operation, or they can be nailed to the blocks or be secured thereto in other manner.

40 The wall blocks 10 are provided at the top of their vertical edges facing each other with rectangular recesses 11 which are adapted to receive a ready cast cross piece 13 formed as a beam, said cross piece forming the upper limit of a window or door opening. Below the window openings there are erected, in addition, between the two special wall blocks 10 one or more ready made wall pieces 14. The wall blocks 15, which have no recesses, are used for constructing such wall portions as have no window or door openings. When the wall has a thickness of about 18 centimeters the wall blocks 15 are preferably made with a width of about 60 centimeters or less.

45 Both the wall blocks 10 and 15 having the height of a full story and the wall pieces 13 provided above the window and door openings are provided on the inside of their upper edge with a rectangular recess 16 extending across the 50 entire width of the block or wall piece respectively. In the erected wall the individual recesses form a common recess extending along the entire length of the wall. On the bottom of said recess there is placed a pressure distributing supporting 55 member for the floor beams consisting of a flat iron 17 or the like having a width equal to the depth of the recess and extending along the entire length thereof. The flat iron 17 is provided with a row of holes adapted to receive 70 screws 18 which after lining up and careful

plumbing of the wall blocks are screwed into the latter. After the flat iron 17 has thus been screwed onto the wall blocks it will serve to hold the upper edges of the blocks in the proper positions.

5 Figure 6 is a part section illustrating the manner of erecting the floor beams; For intermediate walls serving as a support for floor beams extending at both sides from the wall the pressure distributing flat iron or the like is made to extend across the entire width of the wall. Therefore, the wall blocks for such 10 walls are not provided at the top with a rectangular recess but are instead made correspondingly lower. A flat iron 22 for an intermediate wall is shown in Figures 2 and 9.

15 The flat irons 17 and 22 for the outer walls and 20 for the intermediate walls respectively are securely united at their meeting points, as will be clear from Figures 2 and 9, so that the flat irons will form a kind of cap-piece which previous to the filling of the open wall block joints will give 25 to the building the required stiffness. The floor beams 23 are placed on the flat irons and are secured thereto by means of bolts 29 which are screwed into the flat irons.

25 At the bottom adjacent wall sections can, if desired, be united in their lined-up position by means of cramp-irons 26, see Figure 10, which are driven into the wall blocks across the joint openings.

30 After the floor beams have been placed in position and have been screwed onto the cap-piece the joints are filled with a uniting joint filling composition. Preferably the joint openings are initially sealed, for example by means of narrow strips which are pressed into the joints, where- 35 after the joint mortar is poured from above into the closed system of channels formed by the sealing of the joints.

35 A preferred method of externally sealing or closing the joint openings before introducing the 40 joint mortar into the joints is shown in Figures 11 and 12, according to which the joint openings are closed with a solidifying mass 42. The closed channel system formed through the closing of the joint openings is indicated with dotted lines 45 in Figure 12. The channel system is preferably divided into a number of separate branches through fillings 43 applied across the joints at convenient points, preferably simultaneously with the erecting of the wall blocks. Both the 50 mass 42 for closing the joint openings and the mass making up the filling 43 can consist of a quick-binding cement. The closing of the joint openings can be effected by means of a spatula, trowel, or similar tool so that an entirely smooth 55 wall surface is obtained, particularly on the inside of the walls.

When the filling mass closing the joint openings has set and gained sufficient mechanical 60 strength, which when using a quickbinding cement will have taken place after the lapse of less than 24 hours, cement mortar or other suitable liquid binding composition is poured into the joints at the tops thereof, the liquid then flowing down through the vertical joints and into the horizontal joints onto the nearest filling 43 whereafter gradually the entire system of channels communicating with the joint entrance is filled with the binding liquid. On account of the 65 hydrostatic pressure from the casting composition in the vertical channel branch the casting composition in the horizontal channel portions will be subjected to a comparatively high pressure, usually a pressure of about 3 meters of water column, and the casting mass will therefore under 70

75

the influence of said pressure fill out even a very thin joint. To permit escape of air which may have become imprisoned in the joint, narrow openings can be provided at suitable points, said openings being closed as soon as the casting mass starts to flow out therethrough.

After completed grouting or filling of the joints 5

the rectangular recesses 16 and the spaces between the floor beams right above the intermediate walls respectively are filled by means of prop-

erly dimensioned fillers or by a cast-in mass of

porous concrete for the purpose of securing a

plane and smooth upper wall surface before

starting erection of the wall blocks of the next

story.

Wall blocks intended for outer walls can, if de-

sired, be provided in the factory with an external

coating 25 consisting of plaster or other material

as shown in Figures 4 and 5.

In Figures 6 and 7 is shown a floor construction

20 for the building. The floor is composed of blocks

or slabs 30 which are ready made in the factory

from reinforced porous concrete or the like, said

blocks having a length equal to the distance be-

25 between two or more floor beams 23 and a width

determined with regard to the weight of the

blocks and other conditions. The floor blocks are

placed side by side with spacers arranged be-

20 between the individual blocks, said spacers prefer-

ably consisting of ledges 31 cast in one piece with

the floor blocks at the lower edge of the side sur-

face thereof. Between the floor beams 23, which

are I-beams, and the floor blocks is placed a

pad 32 of insulating material, for example strips

35 of a fibrous plate. After the floor blocks have

been placed in position there is forced into the

open joints between the blocks a packing material

33 consisting of a packing cord or the like, for the

purpose of sealing the bottom of the joints, if

necessary. Thereupon a binding composition,

40 for example cement mortar, is grouted into the

joints.

On the lower flanges of the I-beams 23 there

can be placed a counter floor or ceiling consisting

45 of slabs 34 of a fire-proof material, for example

slabs of porous concrete or other artificial stone.

The slabs, which preferably are reinforced to

resist bending, are supported by the floor beams

by means of flat irons 35, which are secured to the

slabs by means of bolts 36 and nuts 37, the flat

irons resting on the lower flanges of the beams

23. The upper surface of the slabs is substan-

50 tially in level with the upper surface of the lower

flanges whereas the lower surface of the slabs is

at a lower elevation than the bottom surface of

the beams, thereby rendering it possible to de-

sign the slabs with a laterally projecting portion

55 38 which extends under the corresponding I-

beam 23 covering the latter and thus providing

a satisfactory protection against fire. The slabs

60 are placed in position from above before the

floor blocks 30 are erected. To obtain improved

sound insulation a filling can be placed on the

counter-floor between the I-beams.

65 The invention is, of course, not limited to the

described embodiment but can be modified in

various ways within the scope of the appended

claims. For instance, it is not necessary to in-

60-65 introduce the binding composition into the joints

only after erection and adjustment of the wall

sections. The binding composition can be in-
7
troduced into the joints in connection with the
erection of the sections provided only that the
binding composition has such properties as not
to solidify until the sections have become adjust-
ed and that it is capable of completely filling out
the joints after displacement of a section in con-
nection with the adjusting operation.

I claim:

1. A method of building houses from story- 10
height wall slabs which have been pre-cast to
accurate dimensions from porous concrete or simi-
lar mouldable stone-like material which com-
prises, erecting the slabs on the foundation wall
or on the walls of a lower story of the building, 15
arranging spacers along the edges of the slabs
so that each slab becomes spaced apart from the
support and from the adjacent slabs to provide
open through-going joint spaces, adjusting the
positions of the individual slabs so that a plane 20
wall surface is formed while maintaining free
play between opposing edges of both horizontal
and vertical joints, steadyng the slabs in the
adjusted position, and finally uniting the slabs
with the support and with each other to form a 25
self-supporting monolithic structure by filling
the joints with a binding mass.

2. A method of building houses from story-
height wall slabs which have been pre-cast with
flat edge surfaces from porous concrete or similar 30
stone-like material which comprises, erecting the
slabs on a supporting wall, arranging spacers at
intervals along the edges of the slabs so as to
provide thin through-going joint spaces of even
thickness between adjacent slabs and between the 35
slabs and the support, adjusting the positions of
the erected slabs and steadyng them in their
adjusted positions, sealing both the horizontal
and the vertical joints on the outside and inside
so as to provide a series of mutually communi-
cating vertical and horizontal closed channels,
40 and finally pouring a fluid binding composition
into the upper open ends of the vertical chan-
nels, whereby the binding composition holds the
wall slabs securely together after setting. 45

3. A method of building houses from story-
height wall slabs which have been precast with
flat edge surfaces from porous concrete or similar
mouldable stone-like material which comprises,
erecting the slabs on a supporting wall of the 50
building, arranging spacers at intervals along the
edges of the slabs so as to provide thin through-
going joint spaces of even thickness between ad-
jacent slabs and between the slabs and the sup-
porting wall, arranging a cap-sill in position on 55
the upper edges of the erected slabs and secur-
ing the floor-beams in position on said cap-sill,
adjusting the positions of the individual slabs
so that the inner faces thereof will be in align-
ment and securing the top portion of each slab 60
in its adjusted position to the cap-sill, sealing
both the horizontal and the vertical joint-spaces
on the outside and inside so as to provide a se-
ries of mutually communicating vertical and hor-
izontal closed channels, and finally pouring a 65
fluid binding composition into the upper open
ends of the vertical channels whereby the bind-
ing composition holds the wall slabs securely to-
gether after setting.

AXEL FRITIOF BOMGREN. 70
